SLIDABLE VANE PUMP

Julius Dusevoir, Dearborn, Mich., assignor to
Consolidated Vultee Aircraft Corp., San Diego,
Calif.

Application October 12, 1945, Serial No. 621,869

8 Claims. (Cl. 103—136)

1

This invention relates to rotary pumps and more particularly to the type in which a vane is slidably mounted in the rotor and engages a cylinder for the rotor.

One object of the invention is to provide a duplex oil pump of this type which is simple in construction and includes rotor for pressure and scavenging units rotating together and mounted on a single shaft.

Another object of the invention is to provide a pressure pump of this type which is provided with a relief valve in one end of the pump-casing which co-acts with the discharge duct in one end of one of the pistons of the rotor.

Another object of the invention is to provide a rotary vane type pump which is extremely simple and compact in construction and is adapted for small units.

Other objects of the invention will appear from the detailed description.

The invention consists in the several features hereinafter set forth and more particularly defined by claims at the conclusion hereof.

In the drawings:

Fig. 1 is a side elevation of a pump embodying the invention, the casing being shown in section.

Fig. 2 is a longitudinal section taken on line 2—2 of Fig. 1.

Fig. 3 is a transverse section taken on line 3—3 of Fig. 1.

Fig. 4 is a transverse section taken on line 4—4 of Fig. 1.

Fig. 5 is a transverse section taken on line 5—5 of Fig. 1.

The invention is exemplified in a construction which comprises a casing 10 which is provided with a cylinder 11 formed in a bushing 12 which is adjacent one end of the casing for a rotary piston for delivering fluid under controlled pressure from the casing; a cylinder 14 for a second rotary piston adjacent the other end of the casing and longitudinally aligned with and of the same diameter as cylinder 11 of a scavenging unit; and an eccentric bearing 15 between said cylinders. The casing has an integral wall 10a adjacent one of its ends and its opposite end is open and provided with an internal screw-thread 16. A head or cap 18 forms a closure for the latter end of the casing 10 and is provided with a screw-thread engageable with the internal thread 16 in the casing for removably connecting the head to the cylinder.

An inlet 13 is formed in the casing for admitting oil to the cylinder 11 and an inlet 13a is formed in the casing for admitting oil to the cyl-

2

inder 14. A pipe 19 is communicatively connected to the chamber in head 18 for delivering fluid under pressure from cylinder 11 to the place of use.

The rotor comprises a shaft 20 which is journaled in a bushing 21 in an extension or sleeve 22 on one end of the casing, a rotary cylindrical piston 28 operating in cylinder 11, and a cylindrical piston 29 operating in cylinder 14, the shaft and pistons being integrally formed and insertable into the casing through the end thereof which is closed by head 18. Shaft 20 projects from the casing and is driven by power from any suitable source through a gear 25 which is secured on a splined portion 26 of said shaft outside of sleeve 22. An annular flange 24 is integrally formed with sleeve 22. An oil seal 23 is confined in sleeve 22 around shaft 20. Pistons 28, 29 are provided with cylindrical peripheries which are concentric with the axis of shaft 20 and eccentric to cylinders 11, 14 for bodily rotation in and tangentially engaging the cylinders, respectively. Pistons 28, 29 are of the same diameter and diametrically oppositely disposed on shaft 20. The rotor, between cylinders 11, 14, is provided with an annular groove 32 in which is confined a split-type bearing-ring 31 which fits in the eccentric bearing 15 and is held in said groove by a retaining spring 33. Piston 29 and ring 31 are of the same diameter as the eccentric bearing 15 in the casing to permit them to be assembled with the casing by insertion of the shaft cylinders 11, 14 and bearings 15 and passing piston 29 into cylinder 14 through eccentric bearing 15 from the end of the casing which is closed by head 18. Ring 31 is split so it can be assembled with the pistons before the rotor is assembled with the casing and is of the same diameter as bearing 15. This construction makes it possible to provide a rotor including an integral shaft and pistons with an intermediate bearing-ring which can be readily inserted and removed from the casing. The pistons are of the same diameter and integrally formed with the shaft 20, for economic fabrication. A longitudinally and radially extending channel 35 and a communicating central port 36 are formed in piston 28 and extend to the end of said piston which is disposed adjacent the head 18. A vane 37 fits and is radially slidable in channel 35 and its outer edge is pressed into engagement with cylinder 11 by a spring 38. Vane 37 is provided on its discharge side with lands 41 between which fluid is forced from the cylinder into channel 35 and port 36 from which it is discharged under pressure. As piston 28 is rotated,

one side of its periphery will slidably engage the cylinder 14 and vane 37 will trap and force the oil in said chamber in advance of the piston between the lands 41 into channel 35 and port 36, from which it will be discharged through the end face of piston 28 adjacent head 18.

In practice, it is desirable to discharge oil from one of the pump cylinders at a predetermined pressure, for example, for lubricating parts. For this purpose a plate or disk 43 slidably fits in the chamber in head 18 and against the discharge side of piston 28 and is provided with a central port 44 communicating with and in offset relation to the end of port 36 in said piston through which oil is discharged from cylinder 11. A spring 45 is interposed between disk 43 and head 18 and normally holds said disk against the outer end face of piston 28. While the pressure of oil from cylinder 11 is normal, disk 43 will permit the oil to pass therethrough for discharge to the lubricating system. When the pressure becomes excessive or greater than the predetermined pressure desired, the increase in the port 36 will force the disk away from the piston and permit some of the oil to flow or by-pass between disk 43 and the end of the piston to channel 35 and thus reduce the flow of the oil through the disk to the discharge pipe 19. The disk is thus responsive to variations in pressure in the oil from port 36 for controlling the pressure of the oil discharged from cylinder 11. A characteristic of this construction is that it is simple, does not require any special ports in the casing, or any enlargement thereof for attaining pressure control. By substituting springs of different magnitudes for the spring 45, the maximum pressure of the discharged oil may be readily varied.

The piston 29 of the scavenging unit is provided with a longitudinally extending radial channel 46 which communicates with a central port 47 which extends through shaft 20 to provide a discharge outlet for oil from cylinder 14. A vane 48 is radially slidable in channel 46 and its outer end is pressed into contact with cylinder 14 by a spring 49. Vane 48 is provided with lands 51 on its pressure side for forcing the fluid in cylinder 14 in advance of vane 48 between lands 51 and into channel 46 and port 47.

When the rotor is driven, the rotating piston 28 and the vane carried thereby will draw oil into cylinder 11 through inlet 13 which will be discharged under pressure from the piston through port 36 at one end of said piston. The pressure responsive disk 43 will control the pressure to a predetermined maximum and by-pass any excess oil between said disk and the end of piston 28 into channel 35, while the oil is discharged from one end of the casing. The rotatable piston 29 will draw fluid through inlet 13a into cylinder 14 and discharge oil through the central port 47 which extends through shaft 20, so that the oil will be discharged from the opposite end of the casing.

The invention exemplifies a rotary pump of the slidable vane-type which includes a piston for discharging oil under regulated pressure and a piston for oil scavenging. The discharge from the cylinders is through opposite ends of the rotor which includes a drive shaft 20 at one end and the discharge of the fluid from the pressure regulated unit is through the casing at its opposite end. The pressure regulating device is in the casing at the end of the piston and is simple in construction and efficient in operation. The pump in its entirety is simple in construction,

formed of few parts, and may be made in small sizes.

The invention is not to be understood as limited to the details described, since these may be modified within the scope of the appended claims without departing from the spirit and scope of the invention.

Having thus described the invention, what I claim as new and desire to secure by Letters Patent is:

1. A rotary pump comprising: a casing provided with a pair of co-axial cylinders, an integral eccentric bearing between the cylinders, inlet ducts extending through the walls of and communicating with the peripheries of the cylinders, respectively; an integral wall and an eccentric bearing at one end of the casing, and a removable head in the opposite end of the casing; a rotor including a shaft journaled in the eccentric end bearing; a pair of co-axial cylindrical pistons on the shaft tangentially engaging the cylinders, respectively; a sectional bearing-member on the rotor between the pistons and fitting in the eccentric bearing between the cylinders; said pistons, bearing-member and the shaft being insertable through the end of the cylinder provided with the removable head; the pistons being provided with separate central longitudinal discharge ducts therein extending to the opposite ends of the rotor, respectively, and radial channels communicating with the central ducts, respectively; and vanes slidably mounted in the channels, engaging the cylinders and provided with ducts therein for discharging fluid under pressure from the cylinders to said central ducts, respectively, the head being provided with an outlet for the discharge of fluid from the central duct in the adjacent piston.

2. A rotary pump comprising: a casing provided with a pair of co-axial cylinders, an integral eccentric bearing between the cylinders, inlet ducts extending through the walls of and communicating with the peripheries of the cylinders, respectively; an integral wall and an eccentric bearing at one end of the casing, and a removable head in the opposite end of the casing; a rotor including a shaft journaled in the eccentric end bearing; a pair of co-axial cylindrical pistons on the shaft tangentially engaging the cylinders, respectively; a sectional bearing-member on the rotor between the pistons and fitting in the eccentric bearing between the cylinders; said pistons, bearing member and the shaft being insertable through the end of the cylinder provided with the removable head; the pistons being provided with separate central longitudinal discharge ducts therein extending to the opposite ends of the rotor, respectively, and radial channels communicating with the central ducts, respectively; and vanes slidably mounted in the channels, engaging the cylinders and provided with ducts in one of the side-faces for discharging fluid under pressure from the cylinders into the discharge ducts, respectively, the head being provided with an outlet for the discharge of fluid from the central duct in the adjacent piston.

3. A rotary pump comprising: a casing provided with a pair of co-axial cylinders, an integral eccentric bearing between the cylinders, inlet ducts for the cylinders, respectively; an integral wall and an eccentric bearing at one end of the casing, and a removable head in the opposite end of the casing; a rotor including a shaft journaled in the eccentric end bearing; a pair of co-axial cylindrical pistons on and integral with the shaft

tangentially engaging the cylinders, respectively; a sectional bearing-member on the rotor between the pistons and fitting in the eccentric bearing between the cylinders; said pistons, bearing-member and the shaft being insertable through the end of the cylinder provided with the removable head; the pistons being provided with separate central longitudinal discharge ducts therein extending to the opposite ends of the rotor, respectively, and radial channels communicating with the central ducts, respectively; and vanes slidably mounted in the channels, engaging the cylinders and provided with ducts therein for discharging fluid under pressure from the cylinders to said central ducts, respectively, the head being provided with an outlet for the discharge of fluid from the central duct in the adjacent piston.

4. A rotary pump comprising: a casing provided with a cylinder and an integral wall at one end thereof and a removable head at its opposite end and provided with an inlet for fluid to the cylinder; a rotor including a shaft eccentrically journaled in the end of the casing having the integral wall and a cylindrical piston co-axial with the shaft, eccentrically disposed in and tangentially engaging the cylinder, and provided with an end-face adjacent the head and with a central duct and a radial channel communicating with said duct, said duct and channel being extended to said end-face of the piston; a radial vane slidably mounted in the channel engaging the cylinder and having ducts therein for discharging fluid under pressure from the cylinder to the central duct; a plate fitting against one end of the piston, provided with a port communicating with the central duct, and responsive to pressure in said duct; and spring-means for pressing the plate against the end face of the piston, the plate being movable by oil pressure for by-passing oil from the central duct to the channel, the head being provided with an outlet for the discharge of fluid from the central duct in the adjacent piston.

5. A rotary pump comprising: a casing provided with a cylinder and an integral wall at one end thereof and a removable head at its opposite end and provided with an inlet for fluid to the cylinder; a rotor including a shaft eccentrically journaled in the end of the casing having the integral wall and a cylindrical piston co-axial with the shaft, eccentrically disposed in and tangentially engaging the cylinder and provided with an end-face adjacent the end of the casing which is closed by the head and with a central duct and a radial channel communicating with said duct, said duct and channel being extended to communicate with said end-face of the piston; a radial vane slidably mounted in the channel engaging the cylinder and having ducts therein for discharging fluid under pressure from the cylinder to the central duct; a plate fitting against one end of the piston, provided with a port communicating with the central duct and responsive to pressure in said duct; and a removable spring in the head for pressing the plate against the end-face of the piston, the plate being movable by oil pressure for by-passing oil from the central duct to the channel, the head being provided with an outlet for the discharge of fluid from the central duct in the adjacent piston.

6. A rotary pump comprising: a casing provided

with a pair of co-axial cylinders and inlet ducts extending through the walls of and communicating with the peripheries of the cylinders, respectively; a rotor including a shaft eccentrically journaled in the casing and a pair of integral cylindrical coaxial pistons eccentrically disposed in and tangentially engaging the cylinders and having separate central discharge ducts extending to the ends of the rotor, respectively; vanes mounted for radial sliding movement in the pistons, having their outer ends engaging the cylinders, respectively, and provided with ducts for discharging fluid under pressure from the cylinders to the central longitudinal discharge ducts, respectively, the casing being provided with an outlet for the discharge of fluid from the central duct in one of the pistons.

7. A rotary pump comprising: a casing provided with a pair of co-axial cylinders and inlet ducts extending through the walls of and communicating with the peripheries of the cylinders, respectively; a rotor including a shaft eccentrically journaled in the casing and a pair of integral cylindrical coaxial pistons eccentrically disposed in and tangentially engaging the cylinders and having separate central discharge ducts extending to the ends of the rotor, respectively; vanes mounted for radial sliding movement in the pistons, having their outer ends engaging the cylinders, respectively, and provided with ducts for discharging fluid under pressure from the cylinders to the central longitudinal discharge ducts, respectively, the casing being provided with an outlet for the discharge of fluid from the central duct in one of the pistons.

8. A rotary pump comprising: casing provided with a pair of co-axial cylinders of the same diameter and inlet ducts extending through the walls of and communicating with the peripheries of the cylinders, respectively; a rotor including a shaft eccentrically journaled in the casing and a pair of integral cylindrical coaxial pistons eccentrically disposed in and tangentially engaging the cylinders and having separate central discharge ducts extending to the ends of the rotor, respectively; a bearing including arcuate sections, for the rotor and disposed in the casing and between the pistons; vanes mounted for radial sliding movement in the pistons, having their outer ends engaging the cylinders, respectively, and provided with ducts for discharging fluid under pressure from the cylinder to the central longitudinal discharge ducts, respectively, the casing being provided with an outlet for the discharge of fluid from the central duct in one of the pistons.
